UNITED STATES PATENT OFFICE.

CHARLES A. LIPPI, OF CAMDEN, NEW JERSEY.

DESIGN FOR A CABINET FOR A RADIO LOUD SPEAKER.

Application filed March 25, 1927. Serial No. 21,321. Term of patent 3½ years.

To all whom it may concern:

Be it known that I, CHARLES A. LIPPI, a citizen of the United States, residing at Camden, in the county of Camden and State of New Jersey, have invented a new, original, and ornamental Design for a Cabinet for a Radio Loud Speaker, of which the following is a specification, reference being had to the accompanying drawing, forming part thereof.

Figure 1 of the drawing is an elevation of the front of the cabinet.

Figure 2, is an end elevation.

Figure 3 is a plan of the bottom.

The large circle, shown in the front elevation, is preferably filled with a sheet of thin material, such as silk.

I claim:

The ornamental design of a cabinet for a radio loud speaker, substantially as shown.

CHARLES A. LIPPI.
